(57) **CLAIM**

The ornamental design for a bruxism treatment apparatus, as shown and described.

DESCRIPTION

FIG. 1 is a perspective view of a bruxism treatment apparatus showing my new design;

FIG. 2 is a front elevation view thereof;

FIG. 3 is a left side elevation view thereof;

FIG. 4 is a right side elevation view thereof;

FIG. 5 is a reduced top elevation view thereof;

FIG. 6 is a reduced bottom elevation view thereof;

FIG. 7 is a back side elevation view thereof; and,

FIG. 8 is a section view taken along plane A-A shown in FIG. 3.

Broken lines in the drawings depict parts of the bruxism treatment apparatus that form no part of the claimed design.

1 Claim, 8 Drawing Sheets(56)
